United States Patent

Des. 241,761

Patented Oct. 5, 1976

241,761

TOY VEHICLE BODY OR THE LIKE

Robert H. C. M. Daenen, Erembodegem, Belgium,
assignor to Dart Industries Inc., Los Angeles, Calif.

Filed Jan. 23, 1975, Ser. No. 543,557

Term of patent 14 years

Int. Cl. D21—01

U.S. Cl. D34—15 AJ

FIG. 1

FIG. 2

FIG. 3

FIG. 4

FIG. 6

FIG. 5

FIG. 1 is a top perspective view of a toy vehicle body or the like showing my new design;

FIG. 2 is a top plan view thereof;

FIG. 3 is a bottom plan view thereof;

FIG. 4 is a side elevational view thereof;

FIG. 5 is a front elevational view thereof; and

FIG. 6 is a rear elevational view thereof.

I claim:

The ornamental design for a toy vehicle body or the like, substantially as is shown.
